UNITED STATES PATENT OFFICE.

JOHN F. COURSON, OF PITCAIRN, PENNSYLVANIA.

DRAFT-GEAR.

1,319,210.

Specification of Letters Patent.

Patented Oct. 21, 1919.

Application filed October 8, 1917. Serial No. 195,233.

To all whom it may concern:

Be it known that I, JOHN F. COURSON, citizen of the United States, residing at Pitcairn, in the county of Allegheny and 5 State of Pennsylvania, have invented certain new and useful Improvements in Draft-Gears, of which the following is a specification.

My invention is an improvement in draft 10 gears of the class utilizing springs and bearing shoes therefor, and actuating mechanism for the bearing shoes operable on buffing or pulling to effect frictional and spring resistance to such strains through the mechanism 15 inclosed within an embracing casing or frame.

The particular objects in view are to provide, in a gear of this type, means for laterally displacing oppositely disposed bearing 20 members whereby to effect bending and also independent frictional movement of a series of assembled leaf springs with variable pressure proportional to the strain, utilizing the drawbar to impart initial or preliminary 25 movement to the actuating elements which engage the springs and also engage co-acting wedge members with accompanying frictional resistance, whereby to effect an increase or reduction in resistance coincident with pressure and release movements. 30 The construction is also adapted to impart either buffing or pulling strains to the car underframe, through the cushioning or resistance mechanism.

These several objects are accomplished in certain preferred forms of the apparatus, as more fully hereinafter described and illustrated in the accompanying drawings, in which:—

40 Figure 1 is a vertical longitudinal sectional view showing a complete gear as assembled, indicated by the section line I, I, of Fig. 2.

Fig. 2 is a horizontal longitudinal sectional view indicated by the line II, II, of 45 Fig. 1, and showing the complete gear and its parts in normal position as assembled.

Fig. 3 is a cross sectional view on the line III, III, of Fig. 1.

50 Fig. 4 is a perspective view of the two-part casing or frame, partly broken away.

Fig. 5 is a similar view of the relatively stationary resistance shoes.

55 Fig. 6 is a similar view of the relatively movable spring-deflecting wedges.

Fig. 7 is a similar view of one of the springs detached.

Fig. 8 is a view similar to Fig. 2 showing the parts in position assumed due to pulling strains. 60

Fig. 9 is a view similar to Fig. 2, showing the parts in normal position, but illustrating the use of a series of tapered spring plates.

Fig. 10 is a view similar to Fig. 2 but showing a modified construction and arrangement of parts in which the resistance shoes are movably connected with the drawbar and the spring deflecting wedges are maintained longitudinally stationary. 65

In the drawings, 2 represents the drawbar of a coupling connected with the front extended strap portions 3, 3, of the movable casing or frame 4 by transverse rivets or bolts 5. Frame 4 as shown is composed of an upper and a lower portion, each connected with the drawbar by said bolts and also connected at the rear end by one or more bolts 6, whereby to maintain it in rigid box-like form. Each member of the frame is provided at its end portions with inwardly 70 extending abutments 7 and 8, respectively, which maintain the intervening spacing and provide for the housing of the several parts, and for end engagement with the spring deflecting wedges hereinafter described. 75

Side portions 9, 9, of the upper and lower members of casing 4 project inwardly toward each other, and abut in the same way. These side portions embrace the longitudinal resistance shoe members 10 which abut 80 by their ends against stops 11, 11, of the center sills 12, to which they are riveted, as shown, and which provide positive engagement with the underframe of the car and resistance against either buffing or pulling 85 strains. Resistance shoes 10 also act to transmit pulling or pushing strains from the gear to the main car underframe, when the parts are in tension, as in Fig. 8.

The sides 9 of the frame 4 extend between 90 the resistance shoes 10 and the inner faces of the center sills, as clearly shown, with sufficient clearance to provide ordinarily for longitudinal movement, but the confronting faces, *i. e.*, the outer faces of the resistance 100 shoes and the inner faces of the frame sides, are corrugated as indicated at 13, so that when these parts are brought into tight frictional engagement, the frictional surface is 105 increased. 110

Extending inwardly from opposite sides from each resistance shoe 10, are the wedge members 14 having series of wedge faces 15 preferably alternating throughout their 5 length, and adapted to interfit with corresponding wedge faces 16 of the spring-deflecting wedges 17. These latter are mounted ^b between the end abutments 7 and 8 of the main casing, whereby to be moved 10 longitudinally thereby in either direction, and are provided on their inner faces each with an undulating or wave-like contour 18, of male and female formation, whereby to correspond with each other and provide be- 15 tween them an alternating or compound curved space. A series of leaf springs 19 are mounted between the wedges 17, each spring being alternately connected at one end and the other to a dowel pin 20 by a 20 perforating hole 21, a corresponding hole 22 at the other end of the leaf spring being slotted to provide for pulling clearance of the other pin. Dowel pins 20 extend from one of the wedges 17 into a receiving hole 25 23 in the other wedge member, whereby to provide for connected movement of the two wedge members together. A plate 24 secured to the lower edges of the center sills supports the gear in place. The series of 30 leaf springs are assembled as shown in Fig. 2 and are substantially straight when the gear is in normal position, and it will be understood of course that a single spring may be used, if desired.

35 Upon the exertion of either buffing or pulling strains, longitudinal movement is imparted to the frame which moves in one direction or the other with relation to the relatively stationary resistance shoes 10.

40 By this means the wedge portions 14 of the shoes, by their faces 15, cause the spring deflecting wedges 17 to move inwardly, one toward the other, as indicated in Fig. 8, thereby compressing and deflecting the 45 series of leaf springs and with a resulting high spring resistance.

At the same time the alternating springs, because of their alternate connection with the pins, effect rubbing movement of the 50 springs in opposite directions throughout the series thereby creating a high frictional resistance. Frictional resistance is also simultaneously generated between the wedge faces of the resistance shoes and the deflecting wedges and between the corrugated faces of the resistance shoes and the main frame, respectively, so that in the aggregate 55 there is a very high frictional and spring resistance generated dependent upon and 60 proportional to the extent of movement of the drawbar.

As shown in Fig. 9, the spring members 19^a are shown as tapered, gradually thickening from the end of their fixed connection 65 with the dowel pins 20^a toward the end of

their free connection with the oppositely located pin 20^a. By this means, longitudinal movement of the spring members will also generate an increased resistance due to the wedging taper of the springs, in proportion to their subjection to the exerted strains. The other parts of the gear operate in the manner already described, and are similarly numbered with the exponent *a*.

In Fig. 10, I have shown a modified construction and arrangement of the parts in which the frame members 4^b are stationarily mounted between the stops 11^b of the center sills 12^b, and the resistance shoes 14^b are themselves relatively movable and connected 75 with the drawbar 2^b by straps 3^b and key 5^b. The spring-deflecting wedges 17^b are maintained stationary by the inclosing frame, abutting against the end portions 7^b and 8^b thereof, which portions are each connected rigidly together by bolts 6^b at each end. The springs 19^b are mounted as in the other forms between these end members 7^b and 8^b and between the spring deflecting wedges 17^b, and the undulating inner faces 80 85 thereof, which, however, are not shown as provided with dowel pins.

The construction and operation of the gear will be readily understood and appreciated from the foregoing description by 95 all those familiar with this class of mechanism. The spring members, by their construction, lying side by side in closely assembled arrangement, provide for both frictional and bending resistance, which 100 increases rapidly in proportion to the increase of strains of service. The construction provides a considerable area of frictional contact throughout the various faces and within a comparatively compact and 105 limited space. The construction is simple and easy to install or repair and is capable of giving high resistance and easy absorption to the strains due to coupling and pulling in train service.

What I claim is:—

1. A draft gear consisting of a casing, a longitudinally disposed leaf spring therein, fixed abutment members for the spring terminals, spring-deflecting members engaging the spring at opposite sides, and means for exerting closing pressure on the spring-deflecting members, adapted for mounting in a car underframe and having attaching portions for connection with a drawbar 115 whereby to transmit drawbar movement thereto to effect displacement of the co-acting portions for connection with a drawbar 120 whereby to transmit drawbar movement thereto to effect displacement of the co-acting parts under buffing or pulling strains.

2. A draft gear consisting of a casing, a series of longitudinally disposed interleaved springs therein, fixed abutment members for the spring terminals, spring-deflecting members engaging the springs at opposite sides, and means for exerting closing pressure on the spring-deflecting members, adapted for 125 130

mounting in a car underframe and having attaching portions for connection with a drawbar whereby to transmit drawbar movement thereto to effect displacement of the 5 co-acting parts under buffing or pulling strains.

3. A draft gear consisting of a casing, a series of longitudinally disposed interleaved springs therein, fixed abutment members 10 for the spring terminals, spring-deflecting wedges engaging the springs at opposite sides, and resistance shoes therefor, adapted for mounting in a car underframe and having attaching portions for connection with a 15 drawbar whereby to transmit drawbar movement thereto to effect displacement of the co-acting parts under buffing or pulling strains.

4. A draft gear consisting of a casing, a 20 series of longitudinally disposed interleaved springs therein, fixed abutment members for the spring terminals, deflecting wedges having undulating faces engaging the springs at opposite sides, and resistance shoes there- 25 for, adapted for mounting in a car under- frame and having attaching portions for connection with a drawbar whereby to transmit drawbar movement thereto to effect dis- placement of the co-acting parts upon buff- 30 ing or pulling strains.

5. A draft gear consisting of a casing, a series of longitudinally disposed interleaved springs therein, fixed abutment members for the spring terminals, deflecting wedges having undulating faces engaging the springs at opposite sides, and resistance shoes there- 35 for having co-acting wedge faces, adapted for mounting in a car underframe and having attaching portions for connection with a 40 drawbar whereby to transmit drawbar movement thereto to effect displacement of the co-acting parts upon buffing or pulling strains.

6. A draft gear consisting of a casing, lim- 45 iting abutments therefor, resistance shoes in sliding frictional engagement with the casing and having inwardly disposed wedge faces, spring deflecting wedges having co-acting wedge faces and alternating project- 50 ing and receding spring engaging faces, a spring member located between said wedges, and fixed abutment members for the spring terminals, adapted for mounting in a car underframe and provided with means for 55 connection with a drawbar whereby to transmit drawbar movement thereto to effect displacement of the co-acting parts upon buff- ing or pulling strains.

7. A draft gear consisting of a casing, 60 limiting abutments therefor, resistance shoes in sliding frictional engagement with the casing and having inwardly disposed wedge faces, spring-deflecting wedges having co-acting wedge faces and spring engaging 65 faces, a series of interleaved spring members

located between said wedges and having alternating connection therewith at one end of each spring member, adapted for mounting in a car underframe and provided with means for connection with a drawbar where- 70 by to effect displacement of the co-acting parts upon buffing or pulling strains.

8. In combination with car framing hav- 75 ing limiting stops, a casing adapted to im- part movement to the underframe through said stops, a pair of resistance shoes engag- ing the casing and having inwardly dis- posed wedge faces, a pair of co-acting spring-deflecting wedges having opposed undulating faces and engaging the casing by 80 their opposite ends, an intervening spring member, fixed abutment members for the spring terminals and means adapted to connect certain of said parts with a drawbar where- 85 by to transmit drawbar movement thereto to effect displacement of the co-acting parts upon buffing or pulling strains.

9. In combination with a car framing hav- 90 ing limiting stops, a pair of resistance shoes engag- ing the limiting stops and hav- ing inwardly disposed wedge faces, a pair of co-acting spring-deflecting wedges hav- 95 ing opposed curved faces, an interposed spring member, and an open-ended casing inclosing said parts having means for con- nection with a drawbar, and adapted to abut toward one or the other of said stops by its opposite edges.

10. In combination with a car framing hav- 100 ing limiting stops, a pair of resistance shoes engag- ing the limiting stops and hav- ing inwardly disposed wedge faces, a pair of co-acting spring-deflecting wedges hav- 105 ing opposed alternating curved faces, an interposed spring member, and an open-ended casing inclosing said parts having frictional engagement with the resistance shoes and means for connection with a drawbar, and adapted to abut toward one or the other of said stops by its opposite edges. 110

11. In combination with a car framing hav- 115 ing limiting stops, a pair of resistance shoes engag- ing the limiting stops and having in- wardly disposed wedge faces, a pair of co- acting spring-deflecting wedges having op- posed curved faces, an interposed spring member, and a casing inclosing said parts having frictional engagement with the re- 120 sistance shoes and end engagement with the spring member and provided with drawbar connecting portions.

12. In combination, a series of interleaved spring plates, a pair of spring-deflecting wedges engaging opposite sides of the spring plate series, a pair of resistance 125 shoes having wedge faces engaging the spring-deflecting wedges and provided with bearing terminals, and a casing in sliding engagement therewith having end engage- 130 ment with the springs and side engagement

with the deflecting wedges and provided with drawbar connecting portions.

13. In combination, a series of interleaved spring plates, a pair of spring-deflecting wedges engaging opposite sides of the spring plate series and provided with pins engaging alternate spring plates at opposite ends, a pair of resistance shoes having wedge faces engaging the spring-deflecting wedges and provided with bearing terminals, and a casing in sliding engagement therewith having end engagement with the springs and side engagement with the deflecting wedges and provided with drawbar connecting portions.

14. In combination, a series of interleaved spring plates, a pair of spring-deflecting wedges engaging opposite sides of the spring plate series, a pair of resistance shoes having wedge faces engaging the spring-deflecting wedges and provided with bearing terminals and longitudinal corrugations, and a casing having co-acting corrugations in sliding engagement therewith having end portions engaging the spring wedges and in side engagement with the deflecting wedges and provided with drawbar connecting portions.

15. In combination with car framing having limiting stops, a pair of resistance shoes engaging said stops and provided with inwardly disposed wedges, a pair of spring-deflecting wedges in engagement therewith having inner opposed curved faces, a series of leaf springs between said faces, a casing embracing said parts in sliding frictional engagement with the resistance shoes and in end engagement with the spring-deflecting wedges, and a drawbar connected with the casing.

16. In combination with car framing having limiting stops, a pair of resistance shoes engaging said stops and provided with inwardly disposed wedges, a pair of spring-

deflecting wedges in engagement therewith having inner opposed curved faces and terminal cross pins, a series of leaf springs between said faces alternately connected with said pins, and a casing embracing said parts in sliding frictional engagement with the resistance shoes and in end engagement with the spring deflecting wedges, and a drawbar connected with the casing.

17. In combination with car framing having limiting stops, a pair of resistance shoes engaging said stops and provided with inwardly disposed wedges and outer frictional grooves, a pair of spring-deflecting wedges in engagement therewith having inner co-acting projections and recesses, a series of leaf springs between said faces, and a casing embracing said parts having grooved sides in sliding frictional engagement with the sides of the resistance shoes and in end engagement with the spring-deflecting wedges, and a drawbar connected with the casing.

18. In combination with an outer pair of resistance shoes having abutting terminals and inwardly disposed wedges, an inner pair of spring-deflected wedges, and a series of interposed leaf springs; a two-part casing having means for attachment to a drawbar, inwardly disposed sides embracing the resistance shoes, end abutments engaging the spring deflecting wedges, and means connecting the parts of the casing.

19. A casing or frame for a draft gear of the class described consisting of an upper and a lower portion each having inwardly turned side portions, inwardly disposed end abutment portions, longitudinal securing portions for a drawbar, and securing bolt holes, substantially as set forth.

In testimony whereof I hereunto affix my signature.

JOHN F. COURSON.
